UNITED STATES PATENT OFFICE.

HERBERT E. FOWLER, OF NEW HAVEN, CONNECTICUT, ASSIGNOR TO THE UNITED STATES PIPE BENDING AND COILING COMPANY, OF CHICAGO, ILLINOIS.

ART OF BENDING AND COILING PIPE.

SPECIFICATION forming part of Letters Patent No. 408,005, dated July 30, 1889.

Application filed April 1, 1889. Serial No. 305,610. (No model.)

To all whom it may concern:

Be it known that I, HERBERT E. FOWLER, a citizen of the United States, residing at New Haven, Connecticut, have invented certain new and useful Improvements in Methods of Bending and Coiling Pipe, of which the following is a specification.

The object of my invention is to bend thin or fragile pipe—such as brass or copper—without reducing it in size or crushing or indenting it. It is common in bending such pipe to fill it with melted resin, which is allowed to cool; and before subjecting the pipe to the bending operation and after the pipe is bent it must be heated in order to melt the resin for removal. It is not possible, however, by any method now in use to successfully bend thin brass or copper pipe without to some extent reducing it in size and indenting its surface. The main difficulty has been in feeding the pipe to the bending mechanism, the feeding having been heretofore accomplished by gripping the end of the pipe after it has passed between the bending-rolls and drawing it forward around the die, or by clamping the bent portion of the pipe with the die and drawing it forward as the die is rotated. These methods were faulty, in that the pipe could only be gripped throughout a small portion of its surface and the force exerted operated to crush or indent it, and also to draw it out or reduce it in size.

By my improved method I am enabled to bend thin or fragile pipe into coils of short diameter without filling the pipe and without injury to it or reducing it in size.

The dominating feature of my invention is the method of feeding the pipe intermittently to the bending mechanism by forcing it forward by means of appropriate gripping devices applied to the straight portion of the pipe.

In the accompanying drawings I have shown appropriate means for carrying out my improved method.

In the drawings, Figure 1 is a plan view, a fragmentary portion of a driving-pulley being broken away; and Fig. 2 is a side view, partly in section.

In said drawings, 3 represents the supporting-table mounted upon a pillar 4.

5 is a stud stepped into the table and bearing upon its upper end the grooved roll or die 6.

7 is a second stud carrying the grooved roll or die 8.

9 is a guide-plate adapted to direct the pipe 55 between the dies.

10 is a sliding block adapted to move in the ways 10^a, and having secured upon its upper face the gripping-jaws 11 11, which will be so secured to the block as to have slight lateral 60 movement.

12 is a second block, also movable within the ways 10^a, and having pivoted to its upper face the short members 13 of the toggle-arms 14, which latter are pivotally connected to the 65 block 10, and having their forward ends projected alongside the jaws 11. The block 12 has a projecting stud 12^a, having on its forward end a pin 12^b, which works in a slot 10^b of the block 10. Block 12 also has a stud 15, 70 which enters a cam-groove 16^a of a cylinder 16, secured to rotate with shaft 17. Movement is imparted to this shaft by a worm-gear 19, operated by a worm-shaft 19^a, driven by means of a pulley 20.

75 The operation of the above-described mechanism is as follows: The pipe will be entered between the gripping-jaws 11 and its forward projected between the guide-plate 9 and the roll 6. Power being applied to the pulley, the described gearing will move the block 12 forward. The first effect of this movement will be to spread the rear ends of the toggle-arms 14 and cause their forward ends to impinge upon the sides of the gripping-jaws 11, 80 whereby the pipe is firmly clamped. A further movement of this block in the same direction will cause it to come in contact with the rear edge of the block carrying the gripping-jaws, and thereby movement is imparted 90 to said block, forcing the pipe forward between the dies and coiling or bending it. This movement is continued until the edge of the block carrying the gripping-jaws has moved up to the guide-plate 9, and by this time the 95 stud 15 has entered the return portion of the cam-slot and the block 12 commences its backward movement, the first effect of which will be to release the gripping-jaws by the release of the toggle-arms 14. The continued back- 100

ward movement will cause the pin 12^b, when it reaches the end of the slot 10^b, to withdraw the block 10, thus sliding the gripping-jaws backward along the pipe in position for a 5 fresh attack.

By the means above described it will be observed that the pipe is forced between the bending-dies instead of being drawn around the same, and as the gripping device may be 10 applied to the straight portion of the pipe the strain may be distributed over such a portion of the surface of the pipe as to avoid reducing, crushing, or indenting it.

I do not intend to limit my invention to the 15 means herein shown for producing this force-feed, nor to the particular dies employed for bending the pipe, as my invention, broadly stated, covers any suitable mechanism where-

by this principle of force-feed is utilized in bending the pipe. The particular mechanism 20 herein shown is made the subject of claim in an application filed of even date herewith, Serial No. 305,611.

I claim—

The herein-described improvement in the 25 art of bending and coiling pipe, which consists in intermittently pushing forward a continuous length of pipe through or between bending devices—such as rolls or dies—whereby the pipe is formed into a series of convolutions.

HERBERT E. FOWLER.
